ABSTRACT

An arrangement for deflecting specified polar molecules in a molecular beam is provided whereby detection and analysis of beam content may be achieved.

ELECTRO DYNAMIC MOLECULAR BEAM DEVICE

BACKGROUND OF THE INVENTION

This invention relates to an arrangement for accomplishing resonance spectroscopy, and more particularly to an improved method and means therefor.

The usual method of operating a molecular or atomic beam apparatus for accomplishing resonance spectroscopy, involves first deflecting the beam to be analyzed by a static-nonuniform magnetic or electric field. Following this is a region containing a dynamic, uniform resonance field which changes the state of the atom or molecule, followed by another region wherein there is a second static-nonuniform deflecting field. When the dynamic uniform field is at resonance for a particular atom or molecule, the subsequent deflection by the following static deflecting field is changed and the number of atoms or molecules reaching a detector is changed.

If deflection could be produced by a nonuniform dynamic field, and the static deflecting fields could be eliminated, it is obvious that by such elimination the cost of the apparatus, its complexity and probably its accuracy would be increased. In the usual case using static-nonuniform fields, the force on a molecule rapidly averages to zero because of oscillation of the dipole moment. That is, the rotating dipole moment of the molecule will go in and out of phase with the oscillating electric field and the net force for any finite time period, as a result is zero. Thus, no deflection is accomplished.

OBJECT AND SUMMARY OF THE INVENTION

An object of this invention is to provide a method and means for defocusing from a molecular beam a desired molecular component thereof using only a nonuniform dynamic resonance field.

Still another object of this invention is to provide a simpler and less complicated arrangement for separating a desired molecular component of a molecular beam which is more inexpensive than those available heretofore.

Still another object of this is the provision of an arrangement whereby the amount that a desired molecule may be deflected from a molecular beam is increased.

Another object of this invention is the provision of an arrangement wherein molecular ions may be deflected from a molecular beam, which were not thought possible heretofore.

Yet another object of this invention is the provision of a novel and useful method and means for analyzing the composition of a molecular beam.

The foregoing as well as other objects of this invention may be achieved in an arrangement wherein the molecular beam desired to be analyzed is introduced into a deflecting chamber wherein there is provided a dynamic uniform electric field which oscillates at a frequency at which a desired molecular dipole can rotate. As a result, the dipole experiences a DC component of force and is deflected appreciably in passing through the field region whereby a means for selecting particular molecules from a beam is achieved. The resonant field may also be magnetic to achieve desired molecular separation. This also produces state selected beams which lend themselves to further study.

The novel features of the invention are set forth with particularity in the appended claims. The invention will best be understood from the following description when read in conjunction with the accompanying drawings.

BRIEF DESCRIPTION OF THE DRAWINGS

FIG. 1 is a cross sectional view of an embodiment of this invention.

FIG. 2 is a cross sectional view along the lines 2-2 of FIG. 1.

FIG. 3 is a perspective view illustrating a ridged waveguide which may be used in this invention in place of the coaxial waveguide.

DESCRIPTION OF THE PREFERRED EMBODIMENTS

In order to determine whether or not a sufficient deflection of molecules in a beam, utilizing solely a dynamic residence field can be achieved, calculations were made on both a classical and quantum mechanical model. These indicated that sizeable deflections can occur for quite realizable power levels. For example, the classical model predicts that the deflection d is given by:

$$D = (2 \times 10^{-9}) (\sqrt{P/r^2}) (u_d l^2)$$

Where P is the power in watts, r the radius of the inner conductor of 50-ohm coaxial deflecting chamber of length l (both in meters), and u_d is the oscillating molecular dipole moment in debyes (1 debye $\cong$ electron charge times bohr radius). If it is assumed that l equals 10^{-1} (10 centimeters), r equals $\frac{1}{2} \times 10^{-3}$ ($\frac{1}{2}$ millimeter) and u_d equals 1 debye and P equals 1 watt, then

$$D \text{ is approximately } 0.2 \times 10^{-3} = 0.2 \text{ millimeters}$$

This amount of beam separation is adequate to get good discrimination from the main beam. The deflected beam will contain only those molecules in resonance with the applied field and may be detected in a number of different ways. FIGS. 1 and 2 illustrate one of many possible ways of constructing an arrangement for achieving such deflection.

In FIG. 1 beam source 10 is representative of the source of molecular beam desired to be analyzed. This may be a gas bottle, a gas discharge tube, a chemical reaction vessel or an oven, etc. This is connected to an inlet valve 12. The inlet valve has its opposite end connected to the vacuum chamber 14. At the coupling of the inner inlet valve 12 to the vacuum chamber, there is an entrance aperture 16, which is arranged to have its central portion blocked by a disc 18, so that a hollow collimated molecular beam is formed.

A coaxial waveguide 20 extends outside the vacuum chamber into the vacuum chamber 14 and is insulatingly supported from the walls of the chamber by insulating supports 22, 24.

One end of the coaxial waveguide is coupled to a variable radio frequency source 26. The other end of the coaxial waveguide is coupled to a radio frequency load 28.

The coaxial waveguide is bent in the manner shown in the drawing so that a length thereof will extend between the entrance port 16 of the vacuum chamber and an exit port 30. A portion of the coaxial waveguide which is opposite to the entrance port 16 also has an

entrance port 32 which is similar to the entrance port 16 having a disc at the center of the opening. This entrance port 32 also assists maintaining the beam hollow and collimated. The waveguide is positioned such that its central conductor 34 is aligned with the center of the hollow molecular beam, represented by the dotted lines 36.

As shown in FIG. 2, which is a view taken along the lines 2-2 of FIG. 1, a vacuum pump 38 is coupled to the vacuum chamber 14 and serves to keep the pressure in the various regions within the vacuum chamber low enough so that no scattering out of the molecular beam occur. The cross-sectional lines shown in FIG. 2 illustrate that the waveguide 20 is provided with slots to enable the vacuum pump to have access to the region contained therein.

The variable rf source applies pulsed or CW electromagnetic radiation within the coaxial waveguide 20, which passes therethrough establishing an electric field and is dissipated in the external rf load 28. The electric field is provided at a frequency corresponding to the resonance frequency of the polar molecules desired to be separated from the molecular beam.

At the end of the interaction region within the waveguide, which is the region between the entrance opening 32 and an exit opening 40, the undeflected remaining portion of the beam 34 impinges on a beam stop portion 42 of the waveguide wall, and ultimately is pumped out of the guide and chamber. However, that portion of the beam which is deflected is deflected toward the center of the hollow beam and passes through the exit opening 40 and thereafter enters through the opening 30, into a detection chamber 44. Detection of the portion of the beam which enters the detection chamber 44 can be done in a number of very well known ways. The molecules which enter the chamber can be ionized by an electron beam and thereafter counted or they may be ionized and put through a quadrupole mass filter and then counted. Since these techniques are well known, they will not be further discussed here. What is significant however, is that by means of the variable RF source 26, an oscillating electric field may be established within the waveguide at one of the frequencies at which molecules desired to be separated out of the electron beam can be made to rotate. As a result these molecules are deflected from the remainder of the molecular beam whereby they can be separated and identified.

FIG. 3 is a perspective view looking into one end of a ridged waveguide 40. This may be used in place of the coaxial waveguide in the vacuum chamber as shown in FIG. 1. The rf field is applied to the ridged waveguide through coaxial connections at both ends of the ridge. These coaxial connections extend through the vacuum chamber walls to a variable rf source and to an rf load respectively.

The beam enters and leaves the ridged waveguide through its open ends. Pumping of this waveguide also occurs through the open ends. The location within the ridged waveguide at which the beam is aimed is the space between the inverted V-shaped top 42 of the central wall 44 and the opposite inverted V-notch 46, in the top wall 46 of the ridged waveguide. Where the beam exits the ridged waveguide there is provided a beam stop for the undeflected molecular beam. The deflected molecules are deflected towards the ridge or the top 42 of the central wall 44. The ridged waveguide will

also have slots in the side walls to enable vacuum pumping of the interior.

Unlike the coaxial waveguide, since no central conductor extends through the interaction region of the ridged waveguide, the molecular beam need not be hollow and therefore the structures shown in FIG. 1 for blocking out the center of the beam may be omitted. The ridged waveguide provides an oscillating electric and magnetic field.

Accordingly, there has been shown and described herein a novel and useful arrangement for separating a desired component for a molecular beam which solely employs a resonant nonuniform dynamic field for achieving such separation. Greater separation is achieved than possible heretofore whereby the usefulness of this technique for analysis is greatly extended.

What is claimed is:

1. Apparatus for separating desired molecules from a molecular beam comprising:

means for establishing an interaction region for said molecular beam comprising a waveguide having a region through which said molecular beam can pass and having an opening at one end to afford entry of said molecular beam into said region of said waveguide,

means for directing said molecular beam to pass through said interaction region,

means for applying a nonuniform oscillating dynamic electric or magnetic field, oscillating at a frequency at which the molecules desired to be separated from said molecular beam are caused to be deflected from the rest of the molecular beam, and means for enabling said deflected molecules to pass from said interaction region while preventing the remainder of said molecular beams from passing from said interaction region, comprising an opening at the other end of said waveguide positioned at a location where only said deflected molecules can pass therethrough.

2. Apparatus as recited in claim 1 wherein said waveguide is a coaxial waveguide.

3. Apparatus as recited in claim 1 wherein said waveguide is a ridged waveguide.

4. Apparatus as recited in claim 1 where there is included a vacuum chamber through which said waveguide passes.

5. Apparatus for separating desired molecules from a molecular beam comprising:

a vacuum chamber having one opening in one wall for affording entry for said molecular beam and a second opening in the opposite wall to afford exit for said desired molecule,

a waveguide having two ends external to said vacuum chamber and extending from one of said ends into said vacuum chamber to said chamber wall opening, then extending through said chamber to the second opening in the opposite wall to provide an interaction region, and then extending outside of said vacuum chamber to the other of said two ends, said waveguide having an entrance opening in the portion of its wall opposite said chamber wall one opening affording entry of said molecular beam into its interaction region and having an exit opening in the portion of its wall which is opposite said second opening in said vacuum chamber wall to afford exit of said desired molecules,

a radio frequency source coupled to said one of said waveguide ends for establishing an electric field in said waveguide at a frequency which will deflect desired molecules from said molecular beam to-

ward said exit opening, and a radio frequency load coupled to said other of said waveguide ends.
